UNITED STATES PATENT OFFICE.

WILLIAM A. TURBAYNE, OF BUFFALO, NEW YORK, AND ALBERT S. HUBBARD, OF BELLEVILLE, NEW JERSEY, ASSIGNORS TO CHARLES M. GOULD, OF NEW YORK, N. Y.

AUTOMATIC REGULATOR FOR ELECTRIC GENERATORS.

SPECIFICATION forming part of Letters Patent No. 732,239, dated June 30, 1903.

Application filed July 31, 1902. Serial No. 117,836. (No model.)

To all whom it may concern:

Be it known that we, WILLIAM A. TURBAYNE, residing at Buffalo, in the county of Erie and State of New York, and ALBERT S. HUBBARD, residing at Belleville, in the county of Essex and State of New Jersey, citizens of the United States, have invented new and useful Improvements in Automatic Regulators for Electric Generators, of which the following is a specification.

This invention relates to an automatic regulator for electric generators, and more particularly to improvements in the regulator described in United States Letters Patent No. 705,487, granted to Charles M. Gould, July 22, 1902, in connection with an electric-lighting apparatus for railway-cars, in which the electric current for the lights is generated while the car is in motion by a dynamo mounted under the car and driven from one of the car-axles and while the car is not in motion by a storage battery, which is charged by the current generated by the dynamo when in action. In the apparatus described in the said application the dynamo is driven by a belt from the car-axle, and an electric motor and connections are provided which move the dynamo toward the car-axle to slacken the driving-belt, so that it will slip and decrease the speed of the dynamo-armature when the speed of the car-axle is greater than necessary for the normal operation of the dynamo, and which move the dynamo in the opposite direction to tighten the belt when the speed of the car-axle decreases to or below the speed required for the normal operation of the dynamo. The motor is driven in one direction by a current from the dynamo, and a reversing mechanism actuated by a solenoid is provided for determining the direction of movement of the dynamo. The solenoid is controlled by a current generated by the dynamo and operates the reversing mechanism to change the direction of movement of the dynamo when the output of the dynamo by reason of the increased or decreased speed of its armature rises above or falls below a predetermined normal value.

One object of the present invention is to provide such a regulating apparatus with means whereby the current entering the bat-

tery as a charge will be automatically reduced accordingly as the electromotive force of the battery rises during the progress of the charge, so that only the necessary amount of power is used and the battery will not be overcharged. Another object is the provision of means whereby the output of the dynamo is increased when the lamps are burned or lamps are added to the work-circuit, so that the burning of the lamps will not impede the charging of the battery.

In the accompanying drawings, consisting of three sheets, Figure 1 is a side elevation, partly in section, of an apparatus embodying the invention. Fig. 2 is an enlarged end elevation of the motor, solenoid, and associated parts, showing the inclosing casing therefor in section. Fig. 3 is an enlarged plan view, partly in section, of the parts shown in Fig. 2. Fig. 4 is a diagrammatic view illustrating the electrical connections.

Like letters of reference refer to like parts in the several figures.

A represents the dynamo; B, the driving car-axle, and b the driving-belt, which runs around pulleys on the car-axle and dynamo armature-shaft to drive the latter. The dynamo is hung by swinging links c from a carriage C, which is mounted to slide toward and from the car-axle on guide-bars c', suspended below the car-bottom.

E represents a shifting-screw shaft, which is journaled in a suitable bearing and has its threaded portion engaging in a screw-threaded opening in a lug e on the dynamo-carriage. The shaft has fixed thereto two ratchet-wheels F and G, the teeth of which extend in opposite directions.

H represents an oscillating pawl-lever pivoted concentric with the shifting-screw and carrying a double pawl I, which is pivoted on the pawl-lever and is provided with oppositely-projecting noses i i', adapted to co-operate, respectively, with the ratchet-wheels F and G. The pawl-lever is oscillated by an electric motor J, the armature-shaft of which is provided with a worm meshing with a worm-wheel j, which is provided with a crank-pin entering a slot in one arm of the pawl-lever. When the pawl-lever is oscillated, if the pawl-

nose i is in engagement with its ratchet-wheel F the shifting-screw will be turned to the right and the dynamo shifted toward the car-axle. If the other pawl-nose i' is in engagement with its ratchet-wheel G , the shifting-screw will be turned in the opposite direction and the dynamo moved away from the car-axle.

K represents a solenoid for shifting the double pawl to throw one or the other of its noses into engagement with the teeth of its coöperating ratchet-wheel. The core k of the solenoid is connected to one arm of a lever k' , the other arm of which is connected to one end of a spring k^2 , fixed at its other end to the double pawl. When the solenoid-core is in its lowest position, the pawl-nose i' will be lowered into operative relation to its ratchet-wheel G and the nose i raised out of operative position. The oscillation of the pawl-lever by the motor will then turn the shifting-screw to the left and move the dynamo away from the car-axle and tighten the belt. When the solenoid-core is raised to its highest position, the other nose i of the pawl will be lowered into engagement with the teeth of its ratchet-wheel, and the shifting-screw will be turned in the opposite direction and move the dynamo toward the car-axle to slacken the belt. When the solenoid-core is lifted only partially or to the intermediate normal position, (indicated in Fig. 2,) both pawl-noses will be out of engagement with their ratchet-wheels and the pawl-lever will oscillate without operating the shifting-screw.

The parts above described briefly, with the exception of the solenoid, which will be presently described, are all shown and fully described in the said application. While the mechanisms of said application are preferred in connection with the present improvements, other mechanisms for accomplishing a similar result could be employed without departing from the scope of this invention.

The solenoid K is provided with a coarse-wire winding K' , interposed in the circuit between the dynamo and the storage battery and traversed by the full current entering said battery, a second fine-wire winding K^2 , connected as a shunt across said battery and acting cumulatively with the coil K' to magnetize and lift the solenoid-core, and a third coarse-wire winding K^3 in the lamp-circuit wound in such a manner as to act differentially to the windings K' and K^2 and neutralize the magnetic effects of said latter windings, and thus lower the solenoid-core.

The electrical circuits for energizing the solenoid-coils and operating the motor are controlled by a centrifugal governor on the dynamo-shaft, which operates cut-outs, as presently described. These parts are shown in the diagrammatic view Fig. 4 and are as follows: L represents the centrifugal governor, and M a movable switch-arm operated by the governor and provided with switch-blades m m' . n n' n^2 n^3 n^4 are contact-plates

arranged opposite to the switch-blades m m' . O represents the lamps or other translating devices, and P one or more storage batteries for maintaining the lights when the dynamo is out of action or is not running at a sufficient speed for the desired voltage. q represents a main-circuit wire connecting the contact n' with the positive pole of the battery, q' a wire connecting the negative pole of the battery with the coarse-wire winding K' of the solenoid, and q^2 a wire connecting the said winding K' with the contact n^4 . q^3 represents a switch for turning the lights on and off. This switch is connected by a wire q^4 and resistance q^5 with the main-circuit wire q and by a wire q^6 with one terminal of the light-circuit, the other terminal of which is connected by a wire q^7 and the third winding K^3 of the solenoid with the wire q' , leading from the negative pole of the battery. r r' represent a shunt-circuit which connects the main-circuit wires q and q^2 across the battery and includes the fine-wire winding K^2 of the solenoid. s is a wire connecting the contact n^2 and positive brush of the dynamo, and s' a wire connecting the contact n^3 and negative brush of the dynamo. The field A' of the dynamo is included in a shunt-circuit connected by a wire t with the contact n and by a wire t' with the main-circuit wire q^2 . u u' represent the operating-circuit for the motor which oscillates the pawl-lever. When the dynamo-shaft has reached a predetermined desired speed, the centrifugal governor is operated to move the switch-arm and carry the blade m against the two contacts n n' , which project nearer to the switch-arm than the other contacts. The battery-current then flows from the positive pole of the battery through wire q , contact n' , switch-blade m , contact n , wire t , dynamo-field A' , wire t' , wire q^2 , coarse-wire winding K' of the solenoid, and wire q' to the negative pole of the battery. The dynamo-field is thus energized, and the dynamo generates a current which flows from the positive brush of the dynamo through the wire s , motor-circuit wire u , motor J , wire u' , and wire s' back to the negative brush of the dynamo. This current starts the motor which oscillates the pawl-lever, and the nose i' of the pawl being down in engagement with its ratchet-wheel G by reason of the weight of the solenoid-core rotates the shifting-screw to the left, so as to move the dynamo away from the car-axle and tighten the belt. The speed of the dynamo-shaft is then quickened sufficiently to cause the centrifugal governor to throw the switch-arm into contact with all of the contact-plates. The current generated by the dynamo then flows from the positive brush of the dynamo through the wire s , contact n^2 , switch-blade m , contact n' , main-circuit wire q to the battery to charge the same, wire q' , first winding K' of the solenoid, wire q^2 , contact n^4 , switch-blade m' , contact n^3 , and wire s' back to the negative brush of the dynamo.

If the lamp-switch q^3 is in position to turn on the lights, a part of the current also flows from the main-circuit wire q through the wire q^4 , resistance q^5 , lamp-switch q^3 , wire q^6 , 5 lamps O , wire q^7 , and the third winding K^3 of the solenoid to the wire q' , and thence back to the dynamo with that part of the current passing through the battery. Current also flows through the motor-circuit in the manner before described and from the positive brush of the dynamo through wire s , contact n^2 , switch-blade m , contact n , wire t , field A' of the dynamo, wire t' , wire q^2 , contact n^4 , switch-blade m' , contact n^3 , and wire s' back 10 to the negative brush of the dynamo. When the dynamo-shaft attains the normal speed necessary to produce a current of the normal value, the current passing through the first winding K' and the shunt-winding K^2 of the 15 solenoid energizes the said windings, which act conjointly to an extent sufficient to lift the solenoid-core to the normal or central position in which both noses of the pawl I are 20 out of operative relation with their ratchet-wheels, as indicated in Fig. 2. The dynamo 25 then remains at a constant distance from the driving car-axle, and the current remains constant unless the speed of the axle changes, the lights are turned on, or the charging of 30 the battery has proceeded to an extent to make a reduction of the current desirable. If the speed of the car-axle increases, the magnetization of the solenoid-windings K' and K^2 will be increased and raise the core 35 until the pawl-nose i engages its ratchet-wheel and turns the shifting-screw to the right, moving the dynamo toward the car-axle until its armature speed is reduced and the current brought back to normal. If the 40 speed of the car-axle decreases, the energization of the said solenoid-windings will decrease until the core drops and throws the other pawl into operation to shift the dynamo in the other direction and increase its armature speed. As the battery electromotive 45 force rises during the charging operation the magnetic effect of the shunt solenoid-winding K^2 increases, which also raises the core, throwing the pawl-nose i into operation to 50 move the dynamo to decrease its speed and output. When the lights are turned on or lamp-load added, the current traversing the third winding K^3 of the solenoid energizes 55 the same, and owing to its differential action relative to the other windings of the solenoid it neutralizes or counteracts the same, permitting the core to again drop and throw in the pawl-nose i' to move the dynamo away from the car-axle, so as to again increase its 60 armature speed and output. Thus the output of the dynamo is kept at the desired value for the work which it has to do. The current is reduced as the battery electromotive force increases, so that the battery is 65 charged under ideal conditions and there is no waste of energy, and, too, when the lights are on and more work is demanded of the

current it is increased, so that the necessary amount of current goes to the lights without reducing the charging-current to the battery. 70

We claim as our invention—

1. The combination of an electric generator, a driving element operatively connected to the generator, mechanism for shifting said generator relative to said driving element to vary the speed of said generator, a storage battery in circuit with said generator, and an electrical device controlling the relative movement of said generator and acting upon 80 a variation of the electromotive force of said battery, substantially as set forth. 75

2. The combination of an electric generator, a driving element operatively connected to the generator, mechanism for shifting said 85 generator relative to said driving element to vary the speed of the generator, a storage battery in circuit with said generator, and an electrical device controlling said mechanism and connected in shunt with said battery- 90 circuit, and which acts upon a variation of the electromotive force of said battery, substantially as set forth.

3. The combination of an electric generator, a driving element operatively connected 95 to the generator, mechanism for shifting the generator relative to said driving element to vary the speed of the generator, one or more translating devices, means for placing said translating device or devices in circuit with 100 the generator, and an electrical device controlling said shifting mechanism for the generator and acting when said translating device or devices are cut in or out of said circuit, substantially as set forth. 105

4. The combination of an electric generator, a driving element operatively connected to the generator, mechanism for shifting said generator relative to said driving element to vary the speed of said generator, translating 110 devices, means for placing said translating devices in circuit with said generator, and an electrical device controlling said shifting mechanism included in said circuit, and acting when said translating devices are cut in or 115 out of said circuit, substantially as set forth.

5. The combination of an electric generator, a driving element operatively connected to the generator, mechanism for shifting said generator relative to said driving element to 120 vary the speed of said generator, a storage battery in circuit with said generator, one or more translating devices, means for placing the same in circuit with said generator, and an electrical device controlling said shifting 125 mechanism connected in shunt with said battery-circuit and included in said translating-device circuit, and which acts upon a variation of the electromotive force of said battery or when said translating devices are cut 130 in or out of said generator-circuit, substantially as set forth.

6. The combination of an electric generator, mechanism for regulating the speed of

the generator, a storage battery in circuit with said generator, one or more translating devices, means for placing the same in circuit with said generator, and a solenoid controlling said speed-regulating mechanism and having a winding connected in shunt with said battery-circuit and a winding acting differentially to said shunt-winding and connected in series with said translating device or devices, substantially as set forth.

7. The combination of an electric generator, mechanism for regulating the speed of the generator, a storage battery in circuit with said generator, one or more translating devices, means for placing said translating device or devices in circuit with said generator, and a solenoid controlling said speed-regulating mechanism, said solenoid having

a winding included in said battery-circuit, a second winding connected in shunt with said battery-circuit, and a third winding acting differentially to said other two windings and connected in series with said translating device or devices, substantially as set forth. 20
